UNITED STATES PATENT OFFICE

114,886

DESIGN FOR A WIND DRIVEN TWIN GENERATOR

Joseph H. Jacobs, Minneapolis, Minn.

Application February 23, 1938, Serial No. 75,354

Term of patent 14 years

To all whom it may concern:

Be it known that I, Joseph H. Jacobs, a citizen of the United States and residing in the city of Minneapolis, county of Hennepin, and State of Minnesota, have invented a new, original, and ornamental Design for Wind Driven Twin Generator, of which the following is a specification, reference being had to the accompanying drawing, forming a part thereof, wherein,

Fig. 1 is a top plan view of a wind driven twin generator showing my design;

Fig. 2 is a side elevational view;
Fig. 3 is a front view;
Fig. 4 is a bottom plan view, and
Fig. 5 is a bottom perspective view with one of the two generators removed.

I claim:

The ornamental design for a wind driven twin generator, as shown.

JOSEPH H. JACOBS.
